UNITED STATES PATENT OFFICE

CLYDE RODERICK WEIHE, OF CONNELLSVILLE, PENNSYLVANIA, ASSIGNOR OF ONE-HALF TO CHARLES WEIHE, OF CONNELLSVILLE, PENNSYLVANIA

METHOD FOR TREATING CONTINUOUSLY-MOVING MATERIAL

Original application filed February 1, 1926, Serial No. 85,369. Divided and this application filed July 9, 1927. Serial No. 204,640.

This invention relates to a method for treating continuously moving material, and is a division of my original application, Serial No. 85,369, filed February 1, 1926.

5 The object of the invention is to provide a method for maintaining a treating agent for continuously moving material in contact therewith to insure thorough and effective treatment of the material by the agent and to 10 avoid the agent passing out with the material. That is to say, the present invention is particularly adapted for use in connection with neutralizing waste waters from mines, mills, factories, furnaces, tan-yards and the 15 like before it enters streams, lakes or rivers to prevent contamination thereof, and contemplates the use of a neutralizing agent to be maintained in effectual contact with the running stream of waste water in such a 20 way that the treating agent is effectually used and will not pass out with the waste into the stream.

While the method herein described may be carried out on apparatus of different structural features and characteristics, nevertheless an example of a type of apparatus for carrying out the method is shown in the accompanying drawings, in which:

Figure 1 is a side elevation, partly in section of the apparatus employed.

Figure 2 is a vertical cross-sectional view taken on the line 2—2 of Figure 1.

Similar reference characters designate corresponding parts throughout the several figures of the drawing.

Referring to the example of the apparatus shown for carrying out the method or process it will be observed that the same includes a rotatably mounted cylinder 1 open at both 40 ends indicated as at 2 and 3 to permit the free passage of air for the purpose of aerating the material, while the entrance or front 2 of the cylinder is located in the plane above that of the lower end 3 and is preferably provided with an inturned flange 4 to prevent the material being treated from splashing out through this end. On the inner face of the cylinder 1 is arranged spiral 45 ribs or flanges 5 which may be either continuous or broken. This rib or flange is pref-

erably made in sections since the upper sections wear out more frequently than the lower and consequently may be replaced more economically. The cylinder is suitably supported with its front end inclined upward 55 as is shown clearly in Fig. 1 and the supports here shown comprise rollers 6 with which is engaged an annular rib or track 7. One set of rollers and track are arranged at each end of the cylinder as is shown clearly in Fig. 1. To take care of the downward thrust of the cylinder 1 the structure shown at 8 is employed which consists of two sections of cones properly tapered to avoid rubbing friction, these cones being numbered 60 9 and 10.

The means for rotating the cylinder 1 comprise, as shown, a circular rack 11 which is preferably made in sections and bolted to the outer face of the cylinder. A sprocket chain 12 is engaged with the circular rack 11 and also with a sprocket wheel 13 fixed to a shaft 14 and driven by a worm wheel 15 actuated through a worm 16. This worm 16 is driven by any suitable means, not shown, 70 a connection for which is illustrated at 17.

A flume 20 is arranged at an incline to discharge into the upper end of the cylinder 1 for feeding to said cylinder the material to be treated. The treating agent for use 80 in connection with the material fed through the flume is also discharged into the flume at the point shown at 21 and passes with the material into the cylinder. Any suitable feeding means for the treating agent may 85 be employed and the feed thereof may be controlled by any suitable means.

While this method is primarily intended for purifying water which has become contaminated by mines, mills, factories or other 90 industrial enterprises before passing it on into streams or other water-ways, it obviously may be employed for treating other material or it may be used for the preparation of water for industrial purposes, such as softening it for domestic use, the mixing of paints, oils, etc.

The treating agent used in connection with the water to be purified is supplied from the receptacle 22 and is usually in the form 100

of solid material which is designed to be brought into intimate contact with the water to be purified and held therein so that it will not pass out with the purified water.

6 The cylindrical drum 1 with the internal spiral ribs is adapted to be turned in such direction as to roll the solids or heavier particles of the treating agent towards the elevated end of the cylinder and retain them until they 10 have been dissolved or worn away to small particles which may then be carried with the liquid passing out through the lower end of the cylinder. The rolling or turning action 15 of the cylinder causes an abrasion between the heavier material and solid particles so as to present an active surface to the liquid.

This rolling action also thoroughly mixes the material to be treated passing through the cylinder with the treating agent rolling 20 and splashing it and returning the larger particles of the treating agent to the upper ends of the sections of the cylinder where they are retained until worn away and acted upon by the liquid.

25 The cylinder may be made of any suitable material adapted to withstand the abrasive action of the treating agent and also that of the chemical action the material being treated and of the treating agent.

30 The size of the cylinder, its length, diameter, details of construction, elevation of intake end, spacing of the spirals, and revolutions of the cylinder will depend on the 35 quantity of liquid to be passed through in a specified time as well as on the kind of liquid and the thoroughness that it is to be mixed or neutralized.

Both ends of the cylinder 1 are made open to provide for a draft of air through the 40 cylinder which will effectively aerate the mixture.

In the operation of the apparatus the driving mechanism or any other that should be used is set in motion by any suitable means 45 to cause the cylinder to revolve and turn on the rollers 6, it being prevented from slipping or rolling to the lower side by the thrust mechanism shown at 9 and 10. The contaminated water indicated at W is admitted through the 50 flume 20 into the revolving cylinder 1 and in passing through the flume the water receives and carries with it the neutralizing material or agent fed from the receptacle 22. The contaminated water with the neutralizing agent 55 having passed into the cylinder 1 flows over the spiral 5 rolling and tumbling and thoroughly mixing with the agent and then passes out of the lower end of the cylinder to any 60 suitable point which may be a stream, basin or settling chamber.

By methods heretofore in use the neutralizing agent was washed away with the water and great quantities lost which was very objectionable because this agent contributed to

the filling up of the settling chambers requiring them to be frequently cleaned out.

The apparatus employed herein is substantially automatic it being of course necessary to set the cylinder rotating mechanism in operation but after this has been accomplished the water flowing in through the flume will carry with it the treating agent and the rotation of the cylinder in the proper direction will while constantly agitating the water passing through it will also return the larger particles of the treating agent to the upper end of the cylinder and retain it at or near the entrance of the contaminated water until the action of the latter will have completely worn away or dissolved such particles.

70 It will thus be seen that one of the important features of the invention is to retain the active treating agent at or near the entrance of the water to be treated by means 75 of the spiral and to rotate the cylinder to retain the neutralizing or treating agent in an active state.

75 Without further description it is thought 80 that the features and advantages of the invention will be readily apparent to those skilled in the art, and it will of course be understood that changes in the form, proportion and minor details of construction may be resorted to, without departing from the spirit 85 of the invention and scope of the appended 90 claims.

I claim:

1. A method of treating a fluid with a 100 soluble solid which consists in introducing the soluble solid into the flowing fluid, causing the fluid and soluble solid to cascade through a chamber, and continuously returning undissolved portions of the soluble solid in a direction counter to the cascading fluid.

2. A method of treating a waste liquid with a 105 soluble solid which consists in introducing the soluble solid into the stream of flowing liquid, causing the liquid and soluble solid to cascade through a chamber and continuously returning undissolved portions of the soluble solid in a direction counter to the cascading liquid.

3. A method of treating waste liquids and the like which consists in introducing the 115 soluble solid into the stream of flowing liquid, causing the liquid and soluble solid to cascade through a chamber in the presence of an air draft and continuously returning undissolved portions of the soluble solid in a direction counter to the movement of the cascading liquid.

In testimony whereof I hereunto affix my signature.

CLYDE RODERICK WEIHE.
